UNITED STATES PATENT OFFICE.

GEORGE W. TUCKER, OF WATERBURY, CONNECTICUT.

DESIGN FOR A PICTURE-HOOK.

SPECIFICATION forming part of Design No. 21,870, dated September 27, 1892.

Application filed July 23, 1892. Serial No. 441,056. Term of patent 7 years.

To all whom it may concern:

Be it known that I, GEORGE W. TUCKER, a citizen of the United States, residing at Waterbury, in the county of New Haven and State of Connecticut, have invented and produced 5 a new and original Design for Picture-Hooks; and I do declare the following to be a full, clear, and exact description of the same, reference being had the accompanying drawings, 10 forming a part thereof.

The leading feature of my design consists in the shape and outline of the hook.

In the accompanying drawings, forming 15 part of this specification, Figure 1 is a representation of my novel design in front elevation, and Fig. 2 is a representation thereof in side elevation.

1 denotes the upper curve of the hook, and 2 the lower curve. The upper curve is flattened and its sides tapered downward and in-

ward toward the lower curve, which is round. The outer face of the lower curve is flattened and tapers upward and inward, so as to correspond substantially in outline with the downward taper of the upper curve. 25

What I claim is—

The design for a picture-hook herein shown and described, the same comprising a flattened upper curve having its sides tapered downward and inward and a rounded lower curve 30 having its outer face flattened and its sides tapered downward and inward to correspond substantially with the taper of the upper curve.

In testimony whereof I affix my signature in 35 presence of two witnesses.

GEORGE W. TUCKER.
